No. 732,124.

PATENTED JUNE 30, 1903.

J. E. SEYMOUR.
AUTOMATIC GAS CUT-OFF.
APPLICATION FILED NOV. 7, 1902.

NO MODEL.

UNITED STATES PATENT OFFICE.

JOHN E. SEYMOUR, OF COLUMBUS, OHIO.

AUTOMATIC GAS CUT-OFF.

SPECIFICATION forming part of Letters Patent No. 732,124, dated June 30, 1903.

Application filed November 7, 1902; Serial No. 130,373. (No model.)

To all whom it may concern:

Be it known that I, JOHN E. SEYMOUR, a citizen of the United States, residing at Columbus, in the county of Franklin and State 5 of Ohio, have invented a certain new and useful Improvement in Automatic Gas Cut-Offs, of which the following is a specification.

My invention relates to the improvement of heat-controlled gas cut-offs of that class in 10 which a valve is controlled by the expansion and contraction of metal; and the objects of my invention are to provide, in connection with a suitable form of gas conductor, valve, and burner, improved means for automatically 15 retaining the valve in an open position while the gas-pressure is sufficient to maintain a proper flame at the burner and to close said valve on a dangerous reduction of said gas-pressure and to produce certain improvements in details of construction, which will be more fully pointed out hereinafter. These objects I accomplish in the manner illustrated in the accompanying drawings, in which—

Figure 1 is a plan view of a gas pipe, valve, and burner having my improvement connected therewith. Fig. 2 is a side elevation of the same. Fig. 3 is an enlarged detail view in elevation, showing the connection between the valve-locking bar and expansion-rod. Fig. 4 is a similar view showing a modification in the manner of connecting said locking-bar and expansion-rod; and Fig. 5 is a detail view in elevation of portions of the expansion-rod-holding arm, showing the manner of adjust- 35 ably connecting the sections of the same.

Similar numerals refer to similar parts throughout the several views.

1 represents a suitably-arranged ordinary gas-supply pipe, one end of which terminates 40 in the form of or is connected with a suitable gas-burner 2. Between the sections of the pipe 1 is interposed a valve-casing 3, in which is provided a valve 4, by means of which the supply of gas to the burner may be regulated. The valve 4 is provided with an outwardly 45 extending stem portion 4^a, from which projects a weight-arm 5, the latter consisting of pivotally-connected sections 5^a and 5^b, the outer section 5^b carrying a suitable weight 5^c. The weighted arm thus provided is inclined 50 upwardly from the valve-stem when the latter is in an open position, and that portion of

said valve-stem which becomes its under side when in an open position is provided, as indicated in dotted lines at 6, with a socket or recess. 55

Connected principally with what we will call the "inner" end portion of the valve-casing 3 is one end of a forwardly or inwardly extending arm 7, the latter preferably comprising sections 7^a and 7^b, adjustably connected, as hereinafter described. 8 represents an expansion-rod which is preferably formed of brass or of other material capable of a comparatively high degree of expansion 60 and contraction. This rod has its inner end rigidly connected with the inner end of the arm 7 and its outer end formed, as indicated in dotted lines in Fig. 3 of the drawings, with a tapering socket 9, which is adapted to receive the pointed or correspondingly-shaped projection 10 on the inner end and lower portion of a valve-locking bar 11, which at a point above said projection 10 is pivoted to the arm 7, as shown at 12. This locking-bar 70 11 has its outer end provided on its upper side with an upwardly-projecting spur or pin 13, which is adapted when said outer end of the bar 11 is properly elevated and when the valve 4 is in an open position to enter the socket 80 or recess 6 of said valve-stem. The outer or forward end of the bar 11 is, however, normally depressed to the position indicated in dotted lines in the drawings by gravity or gravity aided by a spring-strip 14, which has 85 one end secured upon the arm 7 and its outer end portion bearing upon the upper side and outer portion of the bar 11.

In order to provide a desirable adjustment of the expansion-rod, I may employ between 90 the sections 7^a and 7^b of the arm 7 a thumb-nut 15, from opposite sides of which project right and left hand screws 16, which enter correspondingly-threaded end openings in said arm-sections. 95

While in Figs. 1 and 2 of the drawings I have shown a socket connection between the bar 11 and expansion-rod, I have in Fig. 4 of the drawings disclosed a modified connection of these parts, consisting in employing a pivotal connection, such as indicated at 17, between said expansion-rod and locking-bar. It will be observed that the expansion-rod is supported in such relative position with 100

the burner as to insure a desirable heating of said rod from the flame at the burner.

Normally or when the burner is not in operation the connection of the expansion-rod 5 and the locking-bar 11, owing to the length of said rod, is not such as to exert sufficient end pressure on said locking-bar to raise the outer end of the latter until its projection 13 is in engagement with the valve-stem, and 10 the regulation of the contact between said rod and locking-bar may be effected by the turning of the thumb-nut 15.

In utilizing my device the valve is turned to the open position shown in the drawings 15 and the gas ignited at the burner. The heat from the flame at the burner being imparted to the expansion-rod, the latter will expand longitudinally, resulting in such end pressure on the bar 11 as to raise the outer end of the 20 latter and cause the projection 13 to enter the socket 6 of the valve-stem, thus locking the valve in the open position. When the gas is first ignited, however, and before sufficient expansion takes place, the valve may 25 be held in an open position by turning the outer section of the weighted arm 5^b back to the position indicated by dotted lines in Fig. 2 of the drawings; but when the valve has become locked through the medium of the 30 bar 5 this weighted arm may have its outer section thrown outward to the position shown in full lines.

Assuming now that the gas-pressure from any cause is so reduced, automatically or 35 otherwise, as to cause the flame at the burner to go down to a low point or to go entirely out, the reduction in heat will result in the contraction of the expansion-rod and in a consequent dropping of the bar 11 out of engagement with the valve-stem and through 40 action of the weighted arm 5 in said valve being immediately turned to a closed position. By this operation it will be readily understood that where gas is left burning in a

furnace or stove or other gas-consuming burner the gas will be automatically cut off when the pressure thereof is sufficiently reduced. As will be seen, my improved device will be of great utility in cases where the gas-pressure is temporarily so reduced as to cause the flame at the burner to be entirely extinguished.

Having now fully described my invention, what I claim, and desire to secure by Letters Patent, is—

1. In an automatic gas cut-off, the combination with a gas-supply pipe, a burner connected therewith, a valve interposed in said pipe, said valve having an extension provided with a socket and a weight-arm formed of jointed sections extending from said valve extension, of a locking-bar pivoted at one end and having a projection adapted to enter said valve-extension socket and an expansion-rod having one of its ends connected 60 with one end of said locking-bar, substantially as specified.

2. In an automatic gas cut-off, the combination with a gas-supply pipe, a burner connected therewith, a valve interposed in said supply-pipe, said valve having an extension provided with a socket 6 and a weight-arm projecting from said valve extension, of an arm 7 adjustable with reference to its length, a locking-bar pivotally connected with said arm at one end and having a projection at its remaining end adapted to enter the valve-extension socket and an expansion-rod connected at one end with said arm 7 and at its remaining end with said locking-bar, said expansion-rod being formed of material capable of being readily expanded by heat, substantially as specified.

JOHN E. SEYMOUR.

In presence of—

A. L. PHELPS,
W. L. MORROW.
